UNITED STATES PATENT OFFICE.

ISAAC H. WEBB, OF OIL CITY, PENNSYLVANIA.

COMBINED VALVE AND SPRAYING APPARATUS FOR CLEANING OIL-WELLS.

SPECIFICATION forming part of Letters Patent No. 414,464, dated November 5, 1889.

Application filed March 1, 1889. Serial No. 301,688. (No model.)

To all whom it may concern:

Be it known that I, ISAAC H. WEBB, residing at Oil City, in the county of Venango and State of Pennsylvania, have invented a new and Improved Combined Valve and Spraying Apparatus for Cleaning Oil-Well^s, of which the following is a specification.

My invention is in the nature of a valve and spraying device for cleaning the parts off the rock and walls of oil-wells, and which operates by spraying the fluid from the tubing onto the rock and walls of the well.

My invention consists of certain peculiar combinations and novel arrangement of parts, as will hereinafter be fully described in the annexed specification and particularly pointed out in the claims, reference being had to the accompanying drawings, in which—

Figure 1 is a perspective view of my improvement, and Fig. 2 is a longitudinal vertical section thereof.

In the drawings, A denotes a tube-coupling, which is connected with the oil or steam pipes B and B', as shown. The tube-coupling has formed on one of its sides a valve chamber or housing A', which communicates with the interior of the coupling by horizontal apertures a a a.

C denotes an outlet in the lower end of the valve-chamber, which is provided at its inner end with a suitable valve-seat c.

D denotes the valve, provided with a stem d, around which is disposed a coiled spring d', which tends to normally hold said valve in contact with and close the opening C. The stem is extended through a stuffing-box E at the upper end of the chamber A', and has secured at said extended end a jar e, which acts as a drill-jar, and serves to loosen the valve-stem in case the same should stick.

F denotes the operating wire rope, reaching from the jar to the derrick-floor.

H denotes the sprayer, which is formed of a perforated pipe coiled about the lower tube B', its upper end being inserted into the outlet C, as shown.

From the foregoing description, taken in connection with the drawings, the advantages of my improvement will be readily understood.

It will be seen that the valve may be opened or closed at will by means of the rope F, and when opened allows the fluid to flow through the sprayer H on the rock and walls of the well, thereby cleansing them and keeping them free from paraffine. With the same apparatus I am also able to steam the rock by opening the valve and making steam-connections with the tubing above-ground, thereby making the tubing serve a double purpose—viz., for both pumping and steaming—doing away with the expense of an extra line of one-inch pipe, which is generally used for steaming.

The jars e may be made in tubular or other form, and they serve to loosen the valve-stem in case it should stick, and causing it to be started down by a blow, like that of a hammer, in case the spring fails to act, and also starting it in the opening movement.

By connecting the interior of the tube-coupling and the valve-chamber by small horizontal apertures a a, as shown, the same will act as strainers, as nothing can enter the valve-chamber too large to get out through the outlet of said chamber.

Having thus described my invention, what I claim, and desire to secure by Letters Patent, is—

1. An improvement in oil-well cleaners, consisting of a coupling A, adapted to be secured to the meeting ends of two sections of the well-tubing, provided with a main chamber aligning the well-tubing, a lateral valve-chamber provided with a discharge-outlet at its lower end, apertures connecting the main chamber and valve-chamber, a valve operating to normally close the said discharge-outlet, a spraying device connected with the discharge-outlet, and means for operating the valve, substantially as shown and described.

2. The combination, with the well-tubing, of the tube-coupling A, having a valve-chamber provided with a discharge-opening,

2
lateral openings being provided between the interior of the coupling and the chamber, a spraying device connected with the said chamber, consisting of a perforated pipe disposed about the tube and connected at its upper end with the discharge-opening in the chamber, a valve disposed within said chamber,

ber, adapted to normally close said opening, and means for operating the valve, substantially as shown and described.

ISAAC H. WEBB.
